US00D595558S

(12) **United States Design Patent**
Saunders

(10) **Patent No.:** **US D595,558 S**
(45) **Date of Patent:** **** Jul. 7, 2009**

(54) **SKEW RABBET PLANE**

(75) Inventor: **Terry R. Saunders**, North Gower (CA)

(73) Assignee: **Lee Valley Tools, Ltd.**, Ottawa, ON (CA)

(**) Term: **14 Years**

(21) Appl. No.: **29/308,228**

(22) Filed: **Jun. 4, 2008**

(51) **LOC (9) Cl.** **08-03**

(52) **U.S. Cl.** **D8/101**

(58) **Field of Classification Search** **D8/101, D8/51, 14, 98; 30/484, 491, 487, 488, 490**
See application file for complete search history.

(57) **CLAIM**

The ornamental design for skew rabbet plane, as shown and described.

DESCRIPTION

FIG. 1 is a perspective view of the skew rabbet plane of this invention.

FIG. 2 is a left side elevation view of the design for the skew rabbet plane shown in FIG. 1.

FIG. 3 is a right side elevation view of the design for the skew rabbet plane shown in FIG. 1.

FIG. 4 is a top plan view of the design for the skew rabbet plane shown in FIG. 1.

FIG. 5 is a bottom plan view of the design for the skew rabbet plane shown in FIG. 1.

FIG. 6 is a front end elevation view of the design for the skew rabbet plane shown in FIG. 1; and,

FIG. 7 is a back end elevation view of the design for the skew rabbet plane shown in FIG. 1.
